UNITED STATES PATENT OFFICE.

RICHARD A. WAGSTAFF, OF SALT LAKE CITY, UTAH, ASSIGNOR TO AMERICAN SMELTING AND REFINING COMPANY, OF NEW YORK, N. Y., A CORPORATION OF NEW JERSEY.

METHOD AND APPARATUS FOR FEEDING GRANULAR MATERIAL TO CONVEYING ROASTERS.

Application filed June 3, 1925. Serial No. 34,594.

This invention relates to feeding apparatus whereby material may be fed to a receptacle in predetermined quantities and at spaced intervals and comprises an intermediate receiving device adapted to receive material from a suitable source of supply and deliver it intermittently at a predetermined point to a receiving device or receptacle.

- 10 The invention relates particularly to a feeding mechanism for furnaces and the like, having a rotating inlet to receive material intermittently and in predetermined quantities from a moving conveyor. The intermediate receiving device is preferably positioned to receive the material and then deliver it to a passage or a chute communicated with the interior of the furnace in such a manner as to prevent egress of the 15 gases from the furnace and to prevent ingress of air into the furnace during the feeding operation. The intermediate receptacle therefore acts as a seal for the passage or inlet into the furnace during the intervals 20 between the successive periods of delivery of material thereto.

The invention also relates to suitable means for preventing the clogging of the intermediate receptacle by particles of large 25 size by providing a yielding abutment which normally closes the passage by resting against the side of the receiving receptacle and is balanced so as to provide a by-passage in event of the clogging of the intermediate 30 device.

Various other objects and advantages of the invention will be obvious from the following particular description of one form of mechanism embodying my invention or from 35 an inspection of the accompanying drawings; and the invention also consists in certain new and novel features of construction and combinations of parts hereinafter set forth and claimed.

40 In the following description and in the claims parts will be identified by specific names for convenience of expression, but they are intended to be as generic in their application to similar parts as the art will 45 permit.

In the accompanying drawings I have shown for purposes of illustration one form

of mechanism with certain modifications thereof embodying the invention, in which

Fig. 1 is an elevation view in part section showing an embodiment of my invention comprising a cylinder feeder mounted to receive material from an endless conveyor and to discharge the material into a McDougall type roaster, the cylinder feeder embodying my invention and the material carried thereby serving as a seal at the intake end of the roaster, and a driving connection between the roaster center shaft drive and the cylinder feeder whereby the latter is made to feed into a roaster at predetermined intervals in accordance with the rate of movement of the material through the roaster.

Fig. 2 is a sectional view along the line 2-2 of Fig. 1 looking in the direction of the arrows,

Fig. 3 is a transverse vertical sectional view of the rotating cylinder and part of the chute of Fig. 1 with the cylinder in the receiving position,

Fig. 4 is a view similar to Fig. 3 with the cylinder in the discharge position, and

Fig. 5 is a view similar to Fig. 3 showing an alternate embodiment of the gate seal.

In the drawings the McDougall type roaster 1 communicates at the feeding opening 2 in the roof 3 thereof with a feed chute 4 which extends vertically upwards and terminates below the discharge end of the endless belt feeder 6. The latter rotates in a direction indicated by the arrow thereon to carry material such as ore or ore and fuel to the chute 4 into which the material is discharged on the downward turn of the belt conveyor 6. The belt receives the material from an ore concentrate hopper 8 and is driven at a given rate of speed by suitable means not shown.

Within the chute 4 is mounted the hopper 9 which tapers from a cross-section at its top coincident with that of chute 4 to a substantially smaller cross section at its bottom and across which is mounted the hollow cylinder 10, the sides of the hopper 9 being cut out to conform to the shape of the cylinder whereby the latter fits in and forms a closely fitting closure for the lower end thereof.

Journals 12, 12 are provided at either end of cylinder 10 (see Fig. 2) and a driving

sprocket 14 is mounted at one end on the shaft 15. As herein described the cylinder 10 as shown in Fig. 1 is intended to be driven in a clockwise direction. On the side of the 5 hopper 9, from which the cylinder 10 rotates a slide 17 is provided which is coextensive laterally with the side 18 of the hopper and which serves to secure a close fit with the cylinder. The opposite side, 20, terminates 10 at such a distance from the cylinder 10 as to permit the passage of particles of such size as might jam between these two members and obstruct the operation of the feeding apparatus.

15 A gate member 22 pivoted to chute 4 and extending through an opening in the side thereof and throughout the width of the interior thereof prevents the passage of material past this point by bearing against the 20 side of the cylinder. The gate is held in this position normally by the weight 23 to support a normal quantity of material in hopper 9 but is readily movable under unusual pressure to permit the material to 25 pass thereby. The arc shaped closure member 24 serves to seal chute 4 against the passage of gases therethrough at any position into which it may be moved by material from hopper 18.

30 Extending lengthwise of cylinder 10 is the opening 25 for receiving and discharging material carried by the cylinder and this opening extends through an arc approximately about one-fifth of the circumference 35 of the cylinder in order to give proper clearance and ready discharge into the roaster 1.

35 Suitable means not shown which serves to drive the center drive shaft 27 which carries the rabble arms (not shown) of the 40 roaster 1 serves also through the gear 28 on shaft 27, the gear 30 on shaft 31, the pinions 32, 32, the sprocket 33 and the sprocket chain 34 and said gear 14 to drive said cylinder 10 in a clockwise direction and at a rate 45 depending upon the rate of handling of the material by the roaster.

50 In the use and operation of the embodiment of my invention shown in the drawing the rabble arms (not shown) of roaster 1 on shaft 27 are moved to cause movement of material being treated through the roaster in a manner well known in the art. Simultaneously with such movement cylinder 10 is rotated in a clockwise direction at a predetermined speed so that material fed through 55 the hopper 8 onto belt feeder 6 and discharged into chute 4 will pass into cylinder 10 when opening 25 is uppermost in a predetermined quantity and subsequently upon the 60 rotation of the cylinder through a half circle when the opening 25 opens downward will discharge from the cylinder through chute 4 onto the roaster hearth in desired quantities and at predetermined intervals. During this 65 feed the feeding cylinder 10 serves also as

an air seal preventing egress of gases from the roaster or the admission of air into the roaster thus permitting more perfect regulation and control of the draft for combustion in the roaster. The gate 22 being normally held against the side of cylinder 10 also acts in sealing the roaster and at the same time permits the passage past cylinder 10 of large pieces and also avoids the wedging and jamming of particles between cylinder 10 and the lower end of side 20 as would naturally occur with that end of the chute rigidly spaced close to the cylinder.

70 An alternate mounting of gate 22 is shown in Fig. 5 in which it is pivoted to side 20 of hopper 9 and held in a normally closed position by weight 36 and it is obvious that various other changes and modifications may be made.

75 By means of my improved construction, it is obvious that a suitable regulation of the speed of rotation of the feed cylinder relative to the rotation of the hearth, will produce a uniform and automatic feeding of the ore upon the hearth, since the cylinder feeds in rows substantially across width of the hearth itself at the successive points of feed and the periods of revolution of the feed cylinder can be regulated so that the charge therefrom will be delivered at the proper 80 spaced intervals upon the hearth to form a suitable layer.

85 The cylinder provides an automatic seal against ingress of air into the hearth whereby the draft may be definitely and positively 90 regulated. At the same time there is sufficient flexibility of operation in the device to prevent the choking or clogging of the feed passages by masses of ore or by individual 95 large particles.

100 Although I have shown and described and have pointed out in the annexed claims certain novel features of my invention, it will be understood that various omissions, substitutions and changes in the several steps 110 of my process and its operation and in the form and details of the apparatus illustrated may be made by those skilled in the art without departing from the spirit of the invention.

115 I claim:

1. In combination with movable means for receiving and discharging granular material, means in closely spaced relation with first said means for guiding material thereto and serving as a partition between a material receiving space and a material discharging space, a member forming part of the second said means normally next first said means movable for permitting the passage between 120 said material receiving space and said material discharging space of material in excessive sizes or amounts and means tending to hold said movable means in its normal 125 position.

2. In combination with a material treating apparatus, a feeding mechanism therefor comprising movable means for receiving and discharging granular material, means in closely spaced relation with first said means for guiding material thereto and serving as a partition between a material receiving space and a material discharging space, a member forming part of second said means normally next first said means movable for permitting the passage between said material receiving space and said material discharging space of material in excessive sizes or amounts and means tending to hold said movable means in its normal position.

3. In combination, between an ore concentrates hopper and an ore treating furnace, apparatus for receiving ore as it is fed from the hopper and for feeding it to the furnace comprising a conduit therebetween, a movable receptacle member in said conduit, means on said conduit in closely spaced relation to said receptacle member serving with said receptacle as a partition between the hopper end and the furnace end of said conduit, a member forming part of said means normally next said receptacle member movable for permitting the passage into said furnace of material in excessive sizes and amounts, and means tending to hold said movable means in its normal position.

4. The combination between an ore treating furnace having means therein for moving the ore therethrough, and an ore hopper

having means for carrying ore therefrom to the furnace, of means for receiving the ore from said carrying means and discharging it at a predetermined rate to the furnace, comprising a conduit, a movable receptacle member in said conduit, means on said conduit in closely spaced relation to said receptacle member serving with said receptacle as a partition between the hopper end and the furnace end of said conduit, a member forming part of said means normally next said receptacle member movable for permitting the passage into said furnace of material in excessive sizes and amounts, and means tending to hold said movable means in its normal position.

5. In combination with a hopper and a furnace, a flue interconnecting said hopper and said furnace, including mechanism for intermittently supplying material contained in said hopper to said furnace, said mechanism including dividing walls and a material discharging member substantially completely dividing said flue into material receiving and material discharging spaces, one of said walls including a movable member whereby large material may pass around said material discharging member into said furnace, and a weight for urging said movable member toward its normal position.

In testimony whereof I have hereunto set my hand.

RICHARD A. WAGSTAFF.
